UNITED STATES PATENT OFFICE.

FRANK H. NIEMANN, OF PHILADELPHIA, PENNSYLVANIA.

TREMOLO.

Application filed August 4, 1925. Serial No. 48,113.

This invention relates to an improvement in tremolo mechanism for pipe organs which may be so constructed that its movements may be adjusted to any desired speed or beat, 5 and a soft, flexible and uniform pulsation imparted to the tones of the organ pipes or reeds.

An object of the invention is to operate the tremolo pneumatic mechanism through a 10 magnet under the control of the organist.

The invention consists of certain novel features of construction and combination of parts which will be hereinafter described and pointed out in the claims.

15 In the accompanying drawings:

Figure 1 is a view in side elevation of the tremolo box with one side removed to illustrate the arrangement of parts;

20 Figure 2 is a longitudinal vertical sectional view;

Figure 3 is an enlarged detail sectional view showing the mounting of the magnet and armature valve;

25 Figure 4 is an enlarged detail bottom plan view of the tremolo box;

Figure 5 is an enlarged detail view in side elevation showing in dotted lines the ducts or passages for conducting the air from one of the air chambers.

30 The tremolo box consists of a top 10, bottom 11, sides 12, and ends 13, 14. The box may be connected to any of the sources of air supply of the organ such as the wind chest or wind trunk to the side 12, which is 35 provided with an opening 15 for the purpose, so that air under pressure is delivered to the tremolo box at all times.

The box contains a pneumatic in the form 10 of a bellows, comprising a central partition 17 mounted on the bottom 11 of the box and provided with a number of openings 18, 18 therethrough. Connected to the partition is a flexible material 19, such as rubber, cloth or leather, and to the ends of the flexible 15 material are connected rigid blocks or disks 20, 20, constructed in accordance with the shape and formation of the pneumatic. The bellows is opened by springs 21, 21 interposed between the partition 17 and end members or blocks 20. The outermost end member 20 has a valve 22 on the face thereof for closing the opening 23 of the end 13 of the box. The opening 23 is an air outlet opening of sufficient size to reduce the pressure in 5 the box, and when the valve 22 is actuated rapidly will cause a tremolo.

The partition 17 is provided with a passage forming an air duct 24 leading into the bellows, and communicates with a passage 25 formed in the bottom 11 of the box. The 60 passage or duct 25 extends lengthwise of the bottom 11 of the box and communicates with the interior of the box by an opening 26. A plate 27 is applied to the bottom 11 of the box and forms a wall of the duct 25, the 65 plate being securely sealed to the bottom to prevent any escape of air. An opening 28 is formed in the plate 27 directly beneath the opening 26 so that these two openings are in alignment and are controlled by a single 70 valve 29. By referring to Figure 4 of the drawing it will be seen that the duct 25 is larger at one end, or at the point of communication with the openings 26 and 28, and gradually tapers to its other end where it 75 joins the duct 24.

Located within the box and preferably supported by the end wall 14 is a block 30 having a buffer pad 31 at its outer end against which the end member 20 of the 80 bellows may contact when the bellows is expanded. The block 30 is recessed on its lower surface, and the recess is covered by a flexible diaphragm 32 for forming an air chamber 33 in the block. Connected to the 85 diaphragm 32 is a stem 34 to which the valve 29 is connected, and the actuation of the diaphragm by the pressure of air causes the valve to close one or the other of the openings 26 and 28. A port 35 is formed in the 90 block 30 for admitting air to the air chamber 33.

The admission of air to the air chamber 33 through the port 35 is governed by a pivoted or swinging valve, consisting of an 95 arm 36 pivoted at its center between two supporting rails 37, 37 mounted on the block 30. The arm 36 is provided with pads 38 on its under surface and at the ends thereof, one of which pads is seated over the port 35 when 100 the valve or arm is rocked in one direction to prevent the ingress of air to the air chamber 33, while the other pad 38 acts as a cushion for the valve or arm 36 when swung in a contrary direction.

105 The valve arm 36 is actuated by a lever 39, having reduced upper end which fits in an opening formed in a bracket or bearing 40, secured to the inner face of the top 10 of the box. A spring 41 surrounds the reduced 110 portion of the lever and has one end thereof engaging the bearing 40 and the other end a

shoulder 42 on the lever 39, tending to force thereto wires 57 and 58 which lead to a suitable stop or button on the organ (not shown) whereby the magnet may be energized at the will of the organist for raising the valve or causing it to be returned to its seat on the sleeve 53 in producing a tremolo action or for discontinuing such action. It is not considered necessary to illustrate the circuit leading from the magnet to the organ as this may be accomplished in any acceptable manner.

5 The lever 39 is provided with a slot 44 through 70 thereof connected to the inner end member 20 of the bellows and the other end extending through the end 14 of the box. The lever 39 is provided with a slot 44 through 75 which the rod or wire 43 extends. Buttons 45, 45 having screw-threaded engagement 10 with the rod 43 are located on each side of the lever 39 for regulating the stroke of the lever. The position or adjustment of the buttons 45, and the distance they are spaced 15 apart controlling the frequency of actuation of the valve or arm 36 for opening and closing the port 33, and governing the beat or pulsation imparted by the operation of the 20 valve 22.

The end 14 of the box is provided with a recess on its outer face which is covered by a flexible diaphragm 46 producing a second air chamber 47. Mounted over the flexible 25 diaphragm and securing it in place on the end 14 is a plate 48, the plate 48 being securely fastened to the exterior wall of the end member 14 and sealed thereto so that there is no escape of air between the end 14 30 and plate 48. The air from the air chamber 33 is delivered against the outer face of the diaphragm through a duct 49 which extends through an end of the block 30 and end 14 of the box and thence upwardly through the 35 plate 48. An outlet duct or passage 50 extends vertically from the bottom of the plate 48 parallel with the duct 49 and leads to the diaphragm 46. The ducts 49 and 50 are normally sealed against communication by 40 the diaphragm 46, and it is only when the air chamber 47 is exhausted of its air that the air in the chamber 33 may be delivered through the duct 49 against the diaphragm 46, causing the diaphragm to be forced inwardly and allowing the air so delivered to 45 pass to the atmosphere through the duct 50.

50 Mounted on the bottom 11 of the box is a valve casing 51 which is provided with a valve chamber 52. A hollow sleeve 53 is screwed into the lower end of the valve chamber 52 and the upper end of the sleeve has the outer wall thereof tapered in the form of a truncated cone, forming a seat for the armature valve 54. The valve chamber 52 has communication with the tremolo box through a port or hole 55, so that the air in the box may enter the valve chamber 52 for causing the armature valve 54 to be seated. Mounted upon the valve casing 51 55 and extending through hole or port 55 is a magnet 57 which is adapted when energized to lift the armature valve 54 to permit the discharge of air through the sleeve 53 to the atmosphere.

60 The armature valve 56 has connected

wires 57 and 58 which lead to a suitable stop or button on the organ (not shown) whereby the magnet may be energized at the will of the organist for raising the valve or causing it to be returned to its seat on the sleeve 53 in producing a tremolo action or for discontinuing such action. It is not considered necessary to illustrate the circuit leading from the magnet to the organ as this may be accomplished in any acceptable manner.

65 The valve casing 51 has a passage 60 therein which communicates with the valve chamber 52 and with a duct 61 which extends through the bottom 11 of the box and upwardly through the end 14 of the box to the air chamber 47.

The upper or inner surface of the valve casing 51 is provided with a screen 62 for covering the air passages from the box 85 through the port or hole 55 and the duct 61 so that any foreign matter contained in the air leading to the air chamber 52 will be prevented from adhering or interfering with the proper functioning of the valve 54.

70 A recess 63 is formed in the plate 48 for the reception of the outer end of the wire or rod 43. A stop button 64 has screw-threaded engagement with the rod 43 which is adapted to engage the inner surface or wall 90 of the end 14 to limit the movement of the rod in a direction toward the end 14 of the box.

75 In the operation of the device air under pressure is being constantly delivered to the 100 box through the opening 15. Assuming that the organist desired to produce a tremolo the stop or button on the organ would be operated by the organist causing the magnet 56 to be energized thereby actuating and 105 lifting the armature valve 54 from its seat. This movement of the valve 54 would open the passage or ducts 60, 61 to the atmosphere through the hollow sleeve 53 and allow the air in the air chamber 47 to escape. The 110 releasing of the air in the air chamber 47 will permit the air in the air chamber 33, assuming that the valve 36 is closing port 35 of the air chamber 33, to pass through the duct or passage 39 of the diaphragm 46, 115 and allow the air so delivered to pass to the atmosphere through the duct 50. The air in air chamber 33 having been exhausted, the air pressure in the box will now act upon the diaphragm 32 causing valve stem 120 34 to be moved upwardly and the valve 29 to be moved from its seat over the opening 28 and close the opening 26, thereby shutting off the air supply through the passage 125 25 and duct 24 to the bellows.

130 This movement of the valve 29 opens the passage 25 to atmosphere through the opening 28 and allows the air in the bellows to escape to the atmosphere, thereby causing the bellows to collapse, assisted by the air

pressure in the box, and forcing the valve 22 off its seat, permitting the air in the box to escape through the opening 23 for producing the tremolo.

- 5 The collapsing of the bellows causes the rod 43 to be drawn forward, and this movement of the rod 43 causes the lever 39 to be drawn along the surface of the arm 36 and rocking arm for the purpose of uncovering the port 35 of the air chamber 33. Immediately upon opening the port 35 the air in the box enters chamber 33 causing the diaphragm 32 to unseat the valve 29 from opening 26 and forcing it downwardly closing opening 28 and forming a communication between the box and the passage 25 and duct 24 to the bellows through the opening 26. In this manner the bellows is again expended, causing valve 22 to be seated over the opening 23, and the rod 43 will be forced rearwardly carrying the lever 39 therewith and causing the arm 36 to be rocked in a contrary direction for closing the port 35. When this occurs the air in the chamber 33 will again be conducted to the atmosphere through the ducts 49 and 50 and the valve 29 again operated by the diaphragm 32 for uncovering the opening 28 and closing the opening 26 when the bellows will again be collapsed and the valve 22 moved for permitting the escape of air through the opening 23.

The rapidity of the action in causing the valve 22 to be seated and unseated is regulated by the positioning of the buttons 45 on the rod 43 and this adjustment naturally changes the beat and tremolo action which would be produced by the air escaping from the box through the opening 23.

Having described my invention, what I claim as new and desire to secure by Letters Patent is:

1. The combination of an organ tremolo box in which air under pressure is delivered, a pneumatic having a valve actuated thereby for discharging the air through an opening in said box, a valve controlling the admission of air to and from said pneumatic for causing the pneumatic to be expanded and contracted and thereby operating the valve of the pneumatic in the discharge of the air from the tremolo box, and means actuated by the air in the box for operating the controlling valve.

2. The combination of an organ tremolo box in which air under pressure is delivered, a pneumatic having a valve actuated thereby for discharging the air through an opening in said box, a valve controlling the admission of air to and from the pneumatic for causing the pneumatic to be expanded and contracted and thereby operating the valve of the pneumatic in the discharge of the air from the tremolo box, means controlled by the air in the box for operating the control-

ling valve, and means actuated by the pneumatic and associated with said last mentioned means for governing the operation of said means in operating the controlling valve.

3. The combination of an organ tremolo box in which air under pressure is delivered, a pneumatic mechanism in said box including a bellows having a valve actuated thereby for the discharge of air through an opening in said box, a valve for controlling the admission of air to and from said bellows for causing the bellows to expand and contract in the discharge of air from the tremolo box, means controlled by the air in the box for operating the controlling valve, and a magnetic valve controlling the pneumatic mechanism.

4. The combination of an organ tremolo box in which air under pressure is delivered, a pneumatic mechanism in said box including a bellows having a valve actuated thereby for the discharge of air through an opening in said box, a valve for controlling the admission of air to and from the bellows for causing the bellows to be expanded and contracted in the discharge of air from the tremolo box, means controlled by the air in the box for operating the controlling valve, means actuated by the bellows and associated with the said last mentioned means for governing the operation of said means in actuating the controlling valve, and a magnetic valve controlling the pneumatic mechanism.

5. The combination of an organ tremolo box, a pneumatic in said box, a valve for controlling the admission of air to and from said pneumatic, a magnetic valve at the tremolo box, means for operating the magnetic valve for causing the actuation of said controlling valve upon the opening of the magnetic valve, and means controlled by the air in the box for operating the controlling valve, means actuated by the pneumatic associated with said last mentioned means for governing the operation of said means in operating the controlling valve for admitting air to and exhausting the air from said pneumatic.

6. The combination of an organ tremolo box in which air under pressure is delivered, a pneumatic having a valve actuated thereby for discharging the air through an opening in said box, a valve for controlling the admission of air to and from said pneumatic for causing the pneumatic to be expanded and contracted, an air chamber located in the box having a flexible diaphragm to which the controlling valve is connected, said air chamber having an intake port and an outlet duct, means actuated by the pneumatic for admitting air to the air chamber whereby the diaphragm will operate the controlling valve and allow the air in the box to enter the

pneumatic, and for cutting off the supply of air to the air chamber whereby the pressure of air in the box will act upon the diaphragm to cause the controlling valve to shut off the supply of air to the pneumatic and permit the air in the pneumatic to be discharged therefrom.

7. The combination of an organ tremolo box in which air under pressure is delivered, 10 a pneumatic controlling the discharge of air through an opening in said box, means for conducting air from the box to the pneumatic and for discharging the air from the pneumatic to the atmosphere, a valve for controlling the admission of air from the box to said means and the discharge of air from said means to the atmosphere, an air chamber located in the box and having a diaphragm, means for connecting the controlling valve to the diaphragm, said air chamber having an intake port and exhaust duct, a valve for controlling the supply of air to the air chamber through the port, means actuated by the pneumatic for operating the valve for cutting off the supply of air to the air chamber whereby the diaphragm will be actuated by the air pressure in the box for causing the controlling valve to cut off the supply of air from the box to the pneumatic 30 and permitting the exhausting of air from the pneumatic, and for actuating the valve whereby the air will be admitted to the air chamber and acting upon the diaphragm for operating the control valve to admit air to the pneumatic and preventing the discharge of air to the atmosphere.

8. The combination of an organ tremolo

box in which air under pressure is delivered, a pneumatic for controlling the discharge of air through an opening in said box, a valve 40 for controlling the admission of air to and from said pneumatic, an air chamber having a diaphragm connected to the controlling valve for operating the same, said air chamber having an intake port and exhaust duct, means actuated by the pneumatic for controlling the admission of air to the air chamber for causing the operation of the control valve.

9. The combination of an organ tremolo box in which air under pressure is delivered, a pneumatic for controlling the discharge of air through an opening in said box, a valve for controlling the admission of air to and from said pneumatic, an air chamber having a diaphragm connected to the controlling valve for operating the same, said air chamber having an intake port and exhaust duct, means actuated by the pneumatic for controlling the admission of air to the air chamber for causing the operation of the control valve, said box having a second air chamber, a diaphragm for said air chamber, means on said box adjacent said diaphragm provided with a passage leading to the diaphragm and exhaust duct of the first mentioned air chamber and having another passage for conducting the air to the atmosphere, a magnetic valve casing at the tremolo box having communication with the second air chamber, a magnetic valve in the valve casing for controlling the discharge of air from said second air chamber.

FRANK H. NIEMANN.
